CLAIM

The ornamental design for a game ring, as shown and described.

DESCRIPTION

FIG. 1 is a top, front, and left side perspective view of a game ring showing my new design;

FIG. 2 is a top plan view thereof;

FIG. 3 is a front elevation view thereof;

FIG. 4 is a rear elevation view thereof; and,

FIG. 5 is a right side elevation view thereof.

The bottom plan view is the same as the top plan view.
